US00D653326S

(12) **United States Design Patent**
Anderson et al.

(10) **Patent No.:** US D653,326 S
(45) **Date of Patent:** ** Jan. 31, 2012

(54) **INHALER**

(75) Inventors: **Gregor John McLennan Anderson**, Ware (GB); **Matthew Spencer Collins**, Shefford (GB); **David Vincent Elliman**, Halstead (GB); **Richard David Lintern**, Huntingdon (GB); **Andrew Michael Kelly**, Ware (GB); **Allen John Pearson**, Huntingdon (GB); **Paul Kenneth Rand**, Ware (GB); **Mark Digby Teucher**, Bristol (GB); **James Anthony West**, Bristol (GB)

(73) Assignee: **Glaxo Group Limited**, Greenford, Middlesex (GB)

(**) Term: **14 Years**

(21) Appl. No.: **29/391,515**

(22) Filed: **May 10, 2011**

Related U.S. Application Data

(62) Division of application No. 29/277,858, filed on Mar. 12, 2007, now Pat. No. Des. 639,931.

(30) **Foreign Application Priority Data**

Sep. 14, 2006 (GB) 3025928
(51) **LOC (9) Cl.** 29-02
(52) **U.S. Cl.** D24/110
(58) **Field of Classification Search** D24/110; 128/200.23, 200.14, 203.15

See application file for complete search history.

(57) **CLAIM**

The ornamental design for an inhaler, as shown and described.

DESCRIPTION

FIG. 1 is a front perspective view of a first embodiment of the present design;

FIG. 2 is a front view of the first embodiment of the present design;

FIG. 3 is a rear view of the first embodiment of the present design;

FIG. 4 is a side view of the first embodiment of the present design;

FIG. 5 is an opposite side view of the first embodiment of the present design;

FIG. 6 is top view of the first embodiment of the present design;

FIG. 7 is bottom view of the first embodiment of the present design;

FIG. 8 is a front perspective view of a second embodiment of the present design;

FIG. 9 is a front view of the second embodiment of the present design;

FIG. 10 is a rear view of the second embodiment of the present design;

FIG. 11 is a side view of the second embodiment of the present design;

FIG. 12 is an opposite side view of the second embodiment of the present design;

FIG. 13 is top view of the second embodiment of the present design; and,

FIG. 14 is bottom view of the second embodiment of the present design.
